UNITED STATES PATENT OFFICE.

GEORGE B. PILKINGTON, OF NEW BRITAIN, CONNECTICUT, ASSIGNOR TO
THE TRAUT & HINE MANUFACTURING COMPANY, OF SAME PLACE.

BUCKLE.

SPECIFICATION forming part of Letters Patent No. 451,840, dated May 5, 1891.

Application filed February 6, 1891. Serial No. 380,298. (No model.)

To all whom it may concern:

Be it known that I, GEORGE B. PILKINGTON, a citizen of the United States, residing at New Britain, in the county of Hartford and State 5 of Connecticut, have invented certain new and useful Improvements in Suspender - Buckles, of which the following is a specification.

This invention relates to that class of frame-and-lever suspender-buckles carrying cast-offs, the object being to furnish an improved buckle of that class having, besides the other novel features hereinafter set forth, a web-clamping lever adapted to be locked closed by means of the cast-off.

15 In the drawings accompanying and forming a part of this specification, Figure 1 is a front view of an improved suspender-buckle embodying certain features of my present invention, the buckle being shown on a suspender-web. Fig. 2 is an edge view of the same buckle, as shown in Fig. 1. Fig. 3 is a sectional edge view in line *a a*, Fig. 1. Fig. 4 is a view similar to Fig. 3, but showing the suspender-web unclamped. Fig. 5 is a front 20 view of the form of buckle-frame shown in Figs. 1 to 4, inclusive, some details being broken away the better to exhibit the preferred construction. Fig. 6 is a front view of the form of buckle-lever shown in Figs. 1 to 4, inclusive, the retaining-clasp being removed. Fig. 7 is a plan view of the retaining-clasp in 25 blank form. Fig. 8 is a front view, similar to Fig. 1, of a modified and improved form of the buckle. Figs. 9 and 10 are sectional edge views in line *b b* of Fig. 8, illustrative of the operation of one of the features of the invention. Fig. 11 is a front view, similar to Fig. 5, of the form of buckle-frame shown in Figs. 8, 9, and 10. Fig. 12 is a front view, 30 similar to Fig. 6, of the form of buckle-lever shown in Figs. 8, 9, and 10.

Similar characters designate like parts in all the figures.

The buckle consists of a frame having an 45 upper bar, a lower bar, parallel side bars, a ribbed plate extending between the side bars intermediate to the upper and lower bars, and a depending loop intermediate of the length of the lower bar, a web-clamping lever supported on the lower bar, and means for operating the lever and locking the same closed.

The frame is adapted to be made in two forms, illustrated in Figs. 5 and 11, respectively, the form shown in Fig. 5 being considered the simplest one, while the form shown 55 in Fig. 11 comprises certain additional improvements. The top bar B at the right-hand and left-hand ends thereof joins the two side bars 2 and 4, respectively, which are joined at their lower ends to the side portions 3 and 5, respectively, of the lower bar, this being designated in a general way by C. Said lower bar has therein a depending loop D, composed of the loop sides 6 and 8 and the connecting lower end *d*. Intermediate of the length of 60 the side bars 2 and 4 there is fastened to said bars a ribbed plate P, whose ends are clinched over the side bars in a well-known manner (which will be understood by comparison of the several figures of drawings) for the purpose of fixedly locating the plate on the side bars. The rib 16 on said plate is at the upper edge thereof, being usually toothed, as shown, for engaging the suspender-web F. (See Figs. 1 to 4, inclusive.)

In the form of buckle shown in Fig. 5 the free ends of the wire used in the construction of the frame are at the top, being joined by the clasp or tube T (shown in section in Fig. 5) to form a continuous top bar. This form 70 of buckle-frame is illustrated in Figs. 1 to 4, inclusive.

In the improved form of buckle - frame shown in Fig. 11 the wire used in the construction of the frame is joined at the lower 85 end of the depending loop D, the top bar B being a continuous wire, as there shown, and thus requiring no clasp or connection. Said loop, when constructed as in Fig. 11, consists of the two loop sides 6 and 8, having the inwardly-turned ends 6' and 8', respectively, which carry the roll or thimble R, whose purpose is hereinafter more fully set forth.

The buckle-lever consists of the web-clamping bar, downwardly-projecting arms having 95 bearings, whereby the lever is journaled on the side portions 3 and 5, respectively, of the lower bar C of the buckle-frame, and the lever-arm (comprising the sides 10 and 12) extending downward from the bar intermediate 100 of said bearing-arms and terminating at the lower end thereof in a hook, whereby the

cast-off is supported, and whereby the lever itself is locked closed by means of the cast-off. The hook-provided end of the lever-arm extends below the lever-bearings to furnish 5 the leverage necessary for operating the lever, this usually requiring the hook H to be wholly below said bearings.

The more simple form of the buckle-lever is shown in Figs. 8, 9, 10, and 12, wherein the 10 bearing-arms 7 and 9 are straight, as indicated in Figs. 8 and 12, and are joined to the outer ends of the lever-bar E, respectively, through the short connecting lengths 11 and 13. When this form of lever is assembled with the frame, 15 as shown in Fig. 8, the frame and lever being correctly proportioned the one for the other, the lower rounded end e of the hook H bears forcibly against the aforesaid thimble or roller R, thereby offering a considerable resistance 20 to the opening and closing of the buckle-lever. This action is illustrated by the corresponding sectional views, Figs. 9 and 10. In Fig. 10 the buckle-lever is shown closed and projecting downward a little in front of said 25 roller. In Fig. 9 the buckle-lever is shown partially opened, the rounded lower end e of the hook H standing directly on top of the roller. In this latter position the lever is sprung out of its normal shape, as indicated 30 by the dotted lines c c in Fig. 8, which said dotted lines, by contrast with the corresponding solid lines, illustrate the spring action of the clamp-bar during the opening and closing of the lever. Because of that action the lever 35 is also designated as the "spring-lever." When said spring action is not required in its fullest extent, the buckle-lever may be constructed in the form shown in Figs. 1 and 6, wherein the bearing-arms 7 and 9 are 40 brought close together contiguous to the sides 10 and 12, respectively, of the lever-arm, the whole being clasped by the clasp G, Figs. 1 and 2, thereby reducing the elasticity of the structure constituting the buckle-lever. This 45 clasp in its blank form is shown in Fig. 7, it having the side wings w w for clasping over the bearing-bars (shown in Fig. 6) and the extended upper end 15 for clasping over the upper side of the web-clamping bar E. This 50 feature is useful in some styles of buckles, while not necessary in other styles. By means of it a smaller size of wire may generally be used for making the lever.

In using the buckle the lower end of the 55 lever-arm swings through the loop D of the buckle-frame, as will be understood by comparison of Figs. 1 to 10, inclusive. When the lever is closed, the hook H of the lever-arm L stands forward of the loop D of the 60 frame, as shown in Figs. 2, 3, and 10. When the hook is in this position, a suitable cast-off—as, for instance, the ordinary cast-off

ring 14—may be put in place on the hook forward of said loop, as shown in Figs. 1 and 2, thereby locking the lever closed. When the 65 cast-off ring is removed, as in Fig. 3, the lever is then free to be swung on its journal, as indicated in Fig. 4, to release the suspender-web F. The clamp-bar E of the lever stands just below the toothed rib 16 of the frame- 70 plate P and operates when the lever is closed to make a short bend at 17 in the web F just below said rib, as illustrated in Fig. 3. When the lever is opened, as in Fig. 4, the web F naturally assumes a larger curvature, and 75 then may be passed up or down through the buckle in the ordinary manner.

Having thus described my invention, I claim—

1. In a buckle of the class specified, the 80 combination, with a buckle-lever, substantially as described, of the improved buckle-frame consisting of the top bar, the side bars, and the lower bar, said lower bar having 85 therein the depending loop carrying the thimble on the inwardly-turned ends of the loop sides, substantially as described.

2. In a buckle of the class specified, the 90 combination, with a buckle-frame having a back plate, substantially as described, of the improved spring-lever consisting of the clamp-bar E, the bearing-arms connected, substantially as described, to the outer ends of said bar, and the hook-provided lever-arm 95 extending from the bar intermediate of the bearing-arms and reaching below said arms, substantially as described.

3. In a buckle of the class specified, the 100 combination, with a buckle-frame, substantially as described, of the improved buckle-lever consisting of the clamp-bar E, the contiguous lever-arms 10 and 12, having a hook at the lower ends thereof, the bearing-arms 105 7 and 9, lying contiguous to said lever-arms, and the clasp inclosing said lever-arms and bearing-arms, substantially as described.

4. In a buckle, the combination, with a buckle-frame having the lower bar and having the depending loop and the thimble at 110 the lower end of said loop, of the buckle-lever journaled on the lower bar and having the hook - provided lever - arm swinging through the loop, the lower end of the hook being rounded and engaging the thimble on 115 the swinging movement of the lever and the lever being a spring acting to hold the hook in engagement with said thimble, substantially as described.

GEORGE B. PILKINGTON.
